UNITED STATES PATENT OFFICE.

RALPH W. McMULLEN, OF DETROIT, MICHIGAN.

FIRE-EXTINGUISHER SAFETY HOLDER.

Application filed December 12, 1927. Serial No. 239,395.

The object of my invention is to provide a safety holder frame for a special type of fire extinguisher, more specifically set forth in my former application, Serial No. 114,923, 5 that will prevent tampering with the extinguisher in any manner while the same is within the supporting frame.

Another object is to produce a safety supporting frame for a special fire extinguisher 10 that is provided with a sealing lock which will operate in such a manner as to indicate any tampering with an enclosed fire extinguisher, yet will not prevent its easy removal from the frame itself.

15 A still further object is to produce a safety fire extinguisher holder that will conceal the outlet port in a manner to prevent any object being inserted therein.

20 A still further object is to produce a safety fire extinguisher holder adapted for retaining any type of hand extinguisher and providing a suitable sealing and locking device therefor.

25 Another object is to produce a fire extinguisher safety holder comprising means for preventing the fire extinguisher when inserted therein from being retained or turned within the supporting frame.

These several objects are obtained in a preferred form by the construction and arrangement of parts more fully hereafter set forth.

Similar parts on all drawings are marked by similar numerals.

Fig. 1 is a front view of the safety holder 35 with a fire extinguisher placed therein, and shows the special locking and sealing means for preventing tampering with the extinguisher.

Fig. 2 is a side view of the holder and extinguisher shown in Fig. 1, showing the real 40 position of the safety holder as applied to the operating members of the fire extinguisher.

Fig. 3 is a front view of my safety holder frame showing the general construction of 45 same and locking members mounted thereon.

Fig. 4 is a side view of the same frame showing the relative position of the operating part.

Fig. 5 is a cross-sectional view taken on line 50 5-5 of Fig. 2, showing the means of attaching and sealing the operating members of the fire extinguisher.

Fig. 6 is a sectional view taken on line 6-6 55 of Fig. 3, showing the recessed cup attached at the lower end of the safety holder, and the

means for holding the fire extinguisher in a fixed, predetermined position.

Fig. 7 illustrates the special type of operating trigger mounted on the top of the fire extinguisher heretofore referred to in a former 60 application.

I will now describe more fully the detailed construction of my safety device, referring to the drawings and the marks thereon.

My invention will best be understood when 65 described in combination with the operating members of the fire extinguisher itself, as the locking device is especially adapted to this type of extinguisher although it may be modified and applied to other similar types of ex- 70 tinguishers.

The type of fire extinguisher readily adapted to the special feature of my invention is illustrated in Fig. 2 of the drawings, comprising a metal liquid pressure tank —1— formed 75 preferably of cylindrical shaped body and sealed with the end heads —2— and —3—. A plunger pump —4— is mounted within the tank —1— and extended thru the tank head —2— and is provided with an operating han- 80

85 dle —5— mounted on the outer end of a pump plunger rod —6— designed to operate and raise the pressure within the tank —1— when the tank is partially filled with liquid. The extinguisher is provided with a discharge nozzle —7— mounted within the opposite head end —3— and is connected to and regulated by an operating valve —8— which is mounted within the head —2— of the tank 90

95 and is controlled by an operating trigger —9— placed in a convenient position near the handle —5— and operates in a manner that when the pressure is pumped up within the tank —1— partially filled with liquid and the operating valve —8— is opened by the movement of the trigger —9— the chemical liquid within the tank will be discharged thru the nozzle —7— and the extinguisher exhausted, if the valve —8— remains open. It

is the purpose of my special safety holder to 100 prevent anyone tampering with the fire extinguisher when not in use, or unnecessarily exhausting the extinguisher, or making it otherwise useless, and to indicate same should the extinguisher be removed from the safety 105

holder or molested or tampered with in any manner. My special safety holder comprises a frame standard bar —10— preferably made of sheet metal bar and of a length slightly greater than the length of the extinguisher 110

tank to which it is applied. Both the top and the bottom ends —11— and —12— of the standard bar —10— are bent to approximately right angles to the bar, and with a sufficient opening between the ends to admit the extinguisher tank —1— and connecting fittings. The standard bar —10— is provided with screw holes —13— thru the center section of the bar as a convenient means for fixedly attaching the same to permanent supports wherever desired to store the extinguisher, when not in use. Mounted at the bottom end of the standard bar —10— is a cup socket —14—, fixedly attached to the bar end —12— by the rivets —15—, and also preferably made of sheet metal, of a size and shape to receive the discharge nozzle end head —3— of the fire extinguisher tank, and retain the same therein, completely closing the fire extinguisher discharge nozzle —7— and preventing any tampering therewith. The cup socket —14— is formed with sufficiently deep side walls —a— to prevent the removal of the tank —1— therefrom. Across the bottom —b— of the cup socket —14— is formed a ridged member —16— preferably positioned at right angles to the frame end —12—. The ridge —16— is designed to fit and engage a recessed socket groove —17— formed within the head end —3— of the extinguisher tank —1—, for preventing the tank from being turned or moved when once inserted within the safety holder. At the top end of the standard bar —10— is mounted a spring band collar —18— fixedly attached thereto by rivets —19—. The spring collar band —18— is so designed to partially enclose the tank head end —2— when pressed therein and clamped thereon sufficiently to retain the extinguisher with reasonable stability, yet allow it to be withdrawn without applying excessive force. The extinguisher tank —1— being placed therein by merely inserting the tank —1— within the cup recess —14— and placing the tank head —2— within the open ends of the spring collar —18—. The collar band —18— is positioned on the standard bar —10— to extend slightly above the top surface of the tank head —2— and carries a sealed bar —20— pivotally attached to the outer end —d— capable of swinging sidewise to admit the tank head —2— within the collar band opening. In placing the extinguisher within the holder the pump handle —5— must be back to the frame, directly in line with the standard bar —10— and the operating trigger —9— positioned at the front side, approximately at about the center of the open collar band ends —d— and —f—. The pivoted sealing bar —20— is positioned and designed to swing over the top surface of the tank end —2— and adjacent thereto and also to fit and engage a notch —21— formed at the end of trigger —9—, when its opposite end —h— is positioned near end —f— of the spring col-

lar band —18— to form a seal for the bar —20— both ends —f— and —h— are bent outward as shown in Fig. 5 and are connected by a narrow strip of paper —22— wound and glued thereon and of sufficient strength to firmly hold the sealing bar —20— within the trigger notch —21— making it impossible to tamper with the extinguisher, either by removing same from the holder, or pulling the trigger without breaking the paper seal —22—, yet by the use of a paper seal lock which will easily tear, the fire extinguisher is always available in case of necessity and can be easily and quickly removed from the safety frame by simply pulling outwardly on the tank —1—, but if tampered with at any time, it will be revealed by the broken paper seal —22—. The top end —11— of the standard bar —10— is formed with a slotted recess —23— therein sufficient to admit the pump handle —5— and engage the shoulders —26— formed on the pump handle stem which also prevents the extinguisher pressure pump —4— from being operated in any manner, while within the safety frame and in case the pump handle is flattened, as illustrated in Figs. 1 and 2, it will prevent rotation of the pump handle and pump rod itself.

Having fully described my fire extinguisher safety holder, what I claim as my invention and desire to secure by Letters Patent:

1. A safety device adapted for holding a portable fire extinguisher therein, comprising a metal supporting frame having means for fixedly mounting the same on any suitable supports, a socket cup fixedly mounted at the bottom of the said frame for receiving the end of the fire extinguisher tank therein, said socket cup being formed with a ridged member across the bottom face thereof for engaging with a corresponding recess in the fire extinguisher tank, a circular spring collar fixedly mounted at the top end of the said frame, positioned to engage the top end of the fire extinguisher tank when placed therein, a sealing bar pivotally attached to one outer end of the said spring collar, said sealing bar positioned to engage a notched recess in the operating member of the fire extinguisher and a paper seal mounted on the free end of the said sealing bar and fixedly attached to the opposite end of the spring collar, in a manner for sealing and holding the said sealing bar in a fixed position across the fire extinguisher operating member.

2. A safety device adapted for receiving and retaining a portable fire extinguisher therein comprising a metal frame having suitable means for fixedly attaching said frame to any desired supports, a socket cup fixedly mounted on the lower end of the said frame, said socket cup being formed with a perimeter rim and also having a ridged member formed across the base section thereof for fitting and engaging a corresponding depression at the

bottom of the fire extinguisher tank, a slotted 30
arm member formed to receive and retain a
movable pump member of the fire extinguisher
therein at the top end of said frame mem- 35
ber, so designed as to prevent any movement
of the extinguisher pump handle, a spring
collar fixedly attached to the top end of the
said frame and positioned thereon to engage
the top end of the fire extinguisher tank and 40
firmly retain the said fire extinguisher there-
in, the said spring being of a length to par-
tially enclose the tank head, a sealing bar piv-
otally attached to one end of the said spring
collar positioned therein to fit and engage a 45
notched recess in the operating trigger of an
enclosed fire extinguisher, the opposite end
of the said sealing bar positioned adjacent the
opposite end of the spring collar and con-
nected thereto by means of a glued paper seal- 50
ing strip, the ends of said spring collar and
sealing bar, both being formed to prevent the
removal of the glued sealing strip without
tearing of the paper.

3. A safety device adapted for receiving
and retaining a portable tank fire extinguisher
therein, comprising a metal frame having
suitable means for fixedly attaching the same
to any desired support and end support sec- 55
tion fixedly mounted on the lower end of the

said frame suitable for receiving and retain- 30
ing the discharge end of a fire extinguisher
tank therein, means mounted within said sup-
port for preventing the turning of the ex-
tinguisher when inserted therein, said sup-
port frame being extended at the top end 35
thereof and bent at right angles to the frame
stand, said top bend end being slotted for re-
ceiving and retaining the sliding operating
member of the fire extinguisher for prevent-
ing any movement thereof, a semi collar bend 40
section fixedly mounted near the top of the
said frame positioned thereon to receive and
engage the top end of the fire extinguisher
tank, and firmly hold said tank within the
safety frame, a sealing bar mounted across 45
the open ends of the semi collar band section
and attached thereto in a manner for hold-
ing the said sealing band within the notched
recess of the fire extinguisher operating trig-
ger and at least one end of the said sealing 50
bar connected to the collar band ends by a
paper seal securely attached thereto and pro-
vided with means to prevent the removal of
the paper seal when once attached except by
tearing.

In witness whereof, I sign this specifica-
tion.

RALPH W. McMULLEN.
